CAM GRINDING APPARATUS

Clarence J. Green, Worcester, Mass., assignor to
 Norton Company, Worcester, Mass., a corpora-
 tion of Massachusetts

Application March 11, 1935, Serial No. 10,366

12 Claims. (Cl. 51—101)

This invention relates to grinding machines, and more particularly to an apparatus for grinding tapered cams on an automobile camshaft.

Heretofore, numerous machines have been developed for the grinding of an automobile cam-shaft having a plurality of cams formed integrally with the shaft. These machines have comprised manually operated machines in which the work table, the wheel feed, the rocking of the bar, and the shifting of the master cam roller have all been distinct manual and individual manual operations. Other machines have been of the automatic type in which it is merely necessary for the operator to place a camshaft in the machine and start the cycle of operation, and the machine automatically grinds all of the successive cams on the shaft and then stops after the cycle has been completed.

In the prior methods of grinding and apparatus used in carrying out these methods, it has been customary to provide a machine in which the master camshaft and the product camshaft are either in axial alignment or in which master cam-shaft and product camshaft are arranged parallel to each other. The former apparatus is preferred due to the fact that the master shaft in axial alignment with the product shaft may be locked rigidly together so that lost motion in the driving mechanism is entirely eliminated.

Up to the present time, the common practice in the automobile engine design has called for a camshaft in which all elements of the surface of the cam lie in parallel planes to the axis of rotation of the shaft. In other words, each cam is straight or of the same dimensions at each end thereof. In the automotive engine employing such a camshaft, it has been found that the tappet engaging the cam is worn away in a path which engages the cam on the camshaft. It is rapidly becoming the standard design, however, to overcome this difficulty and to provide a tapered cam which engages only one portion of the tappet. The tappet and cam are so arranged that the cam tends to rotate the tappet slowly while in use so that instead of having excessive wear on one portion of the tappet head, the cam rotating the tappet causes a more or less uniform wear on the surface of the tappet head.

It is the primary object of this invention to provide a simplified method and apparatus for grinding a plurality of tapered cams which are integrally formed on a camshaft.

It is a further object of this invention to provide a cam grinding apparatus in which the axis of the camshaft being ground is swivelled at an

angle to the axis of the grinding wheel by an amount corresponding to the taper desired to be produced on the cams being ground.

It is a further object of this invention to mount the camshaft to be ground with its axis at an angle to the axis of the grinding wheel and to provide master cams of varied or stepped diameters which allows the cams on the camshaft to be ground while rocking the rock bar through a greater or lesser distance in grinding successive cams, so that all of the cams may be successively ground by utilizing a single stop on the wheel feeding mechanism.

Other objects will be apparent from the foregoing disclosure.

One embodiment of this invention has been illustrated in the accompanying drawings, in which like reference numerals indicate like parts:

Fig. 1 is a somewhat diagrammatic top plan view of a simplified form of a machine embodying this invention;

Fig. 2 is a front elevation of a machine embodying this invention, on a reduced scale, and having parts broken away to more clearly show the construction; and

Fig. 3 is a fragmentary perspective view illustrating the mechanism for indexing the master cam roller.

The present invention relates to a method and apparatus for grinding a plurality of tapered cams on a camshaft by a simple method which permits the use of a single feed stop on the wheel feed mechanism and employs a cylindrical wheel which permits a reciprocation of the wheel during grinding to take up the grinding line and produce the desired fine finish on the cam being ground.

Broadly, this invention comprises a cam grinding machine in which the axes of the grinding wheel and the camshaft being ground are set at an angle to each other so that the cylindrical operative face of the grinding wheel will grind a predetermined taper on the periphery of the cam being ground. A set of master cams or forms of successively varying or stepped sizes serve to cause a relative approaching and receding movement between the grinding wheel and the cams being ground, the variations in the size of the successive master cams being such as to compensate for the angular position of the axes of the camshaft and grinding wheel.

As illustrated in the drawings, a machine embodying this invention comprises a base 10 having a longitudinally traversable work supporting table 11 which is supported on ways 12 and 13 55

on the base 10. A rotatable grinding wheel 15 is supported on a wheel spindle 16 which is journaled in bearings 17 and 18. The bearings 17 and 18 are integral with a transversely movable 5 wheel slide 19 which is supported on the base 10 by a V-way 20 and a flat way 21.

Wheel spindle reciprocation

The grinding wheel spindle 16 and bearings 17 10 and 18 are preferably so arranged that the spindle may be reciprocated within its bearings during the grinding operation. A wheel spindle reciprocating mechanism 22 is fixedly mounted on the wheel slide 19. A control lever 23 serves 15 to stop and start the reciprocation of the spindle as desired. Details of the mechanism have not been illustrated since this mechanism is not a part of the present invention. For details of construction of this mechanism, reference may be 20 had to the prior patent to Belden and Flygare No. 1,584,717 dated May 18, 1926.

Wheel feed

The grinding wheel slide 19 is arranged for a 25 transverse feeding movement relative to the base in order that the grinding wheel may be fed toward the work to the required extent to accurately size the work being ground. Any of the well-known feeding mechanisms may be employed to cause a precise transverse movement 30 of the slide 19. Since the feeding mechanism in itself is not a part of the present invention, the actual wheel feed mechanism has not been shown in detail. The feeding mechanism, as 35 illustrated, is identical with the wheel feeding mechanism shown in the U. S. Patent to Trefethen and Belden No. 1,783,755 dated December 2, 1930, to which reference may be had for details of the wheel feeding mechanism not 40 shown in the present drawings. The wheel feeding mechanism consists of a half nut 25 depending from the wheel slide 19 and engaging a feed screw 26 which is rotatably mounted in the base of the machine. The outer end of the feed 45 screw 26 carries a gear 27 which in turn meshes with a gear 28 rotatably mounted on a stud 29. A manually operable feeding wheel 30 is also rotatably mounted on the stud 29 and is preferably fixed to gear 28 so that rotation of the hand 50 wheel 30 serves to cause a transverse movement of the wheel slide 19 either toward or from the work, as desired, depending on the direction of rotation of the feed wheel 30. The usual micrometer adjusting mechanism 31 is provided on 55 hand wheel 30 which serves to accurately position a stop abutment 32. The abutment 32 cooperates with a stop arm 33 which is pivotally mounted on a stud 34 and serves to positively limit the rotary movement of the feed wheel 30 60 so as to stop the infeeding movement of the grinding wheel 15 when the work piece has been ground to the required size. Details of the micrometer adjustment 30 have not been illustrated, since this feature is not part of the present invention. This construction is substantially that shown in the prior U. S. Patent to Norton No. 762,838 dated June 14, 1904, to which reference may be had for details of construction.

The grinding wheel may be rotated by any 70 suitable source of power (not shown) by means of a pulley 40 mounted on the wheel spindle 16. The pulley 40 may be operatively connected to an electric motor on the wheel slide or by means of a belt to an overhead driving shaft. 75 Such illustration has been omitted, since this

drive does not constitute any part of the present invention.

The work table 11 serves as a work support and in the present construction serves as a support for a swivel table 45 which is pivoted on a stud 46 and arranged to be swivelled, about the vertical pivot stud 46, to the desired extent and then locked in adjusted position. The swivel table 45 in turn serves to support the work holding apparatus which comprises a rock bar 49. The 10 rock bar 49 has reduced end portions or trunnions 50 and 51 journaled in brackets 52 and 53 which are fixedly mounted on the swivel table 45. The rock bar 49 is provided with a headstock member 55 and a footstock 56 which are 15 arranged to rotatably support a camshaft 57 for a grinding operation. A master camshaft 54 is rotatably supported in the headstock 55 and is located in axial alignment with the headstock center 58 and footstock center 59 so that the 20 master camshaft and the product camshaft are in axial alignment with each other. A driving dog 60 is operatively connected to the camshaft being ground and serves to form a rigid driving connection between the master camshaft 25 54 and the product shaft 57.

In order that a rocking motion may be transmitted to the rock bar 49 so as to produce the desired contour on the cams being ground, a rotatable master cam follower 65 is slidably mounted on a shaft 66 which is rotatably journaled in brackets 67 and 68. The brackets 67 and 68 are rigidly fixed to the swivel table 45. The master camshaft 54 is in turn operatively connected with a drive shaft 70 which may be 35 rotated by a pulley 71 (Fig. 1) from any suitable source of power, such as an overhead drive shaft or the like.

Traverse mechanism

In order that the table 11 may be traversed longitudinally relative to the base 10, a traverse mechanism is provided which may comprise a manually operable hand wheel 80 mounted on a shaft 81 and carrying a gear 82. The gear 82 45 meshes with a gear 83 mounted on shaft 84. The shaft 84 carries a gear 85 meshing with a rack bar 86 depending from the under side of the table 11. It will be readily apparent from the foregoing disclosure that rotation of the 50 traverse wheel 80 serves to cause a longitudinal traversing movement of the table 11.

Master cam follower—Index mechanism

In the preferred construction, the master cam 55 follower or roller 65 is arranged for automatic indexing so that when the work table 11 is traversed longitudinally to present a given cam in operative relation with the grinding wheel, the master cam roller or follower 65 is indexed 60 automatically into operative relation with the corresponding master cam 72 on the shaft 54. The automatic indexing mechanism in the present illustration is identical with that shown in the prior United States Patent to Trefethen and Belden No. 1,783,755 dated December 2, 1930. Details of this construction have not been illustrated completely, since reference may be had to the prior patent for details not readily disclosed in the present case. This mechanism, 70 as shown in Fig. 3, may comprise a yoke 73 which serves to engage the side faces of the roller or follower 65 so as to slide it longitudinally on the shaft 66. The yoke 73 is fixed to a rack bar 74. The rack bar 74 is slidably mounted in a sup- 75

port 75. A pinion 76 meshes with the rack 74 and is mounted on a stud 77 which carries a gear 78 meshing with a gear 79. The gear 79 meshes with a gear 81 which in turn carries a star wheel (not shown) arranged to be engaged by adjustable dogs 88 which are adjustably positioned on a bar 89 carried by a bracket 90 fixed to the base 10. It will be readily appreciated from the foregoing disclosure that when the table 11 is moved longitudinally, the star wheel engaging the dogs 88 on dog bar 89 serves to rotate the train of gears 81, 79 and 78 to transmit a longitudinal movement to rack 74 so as to automatically index the master cam roller 65 as the table is moved longitudinally to position it in operative relation with the master cam corresponding with the product cams to be ground. For further details of the automatic indexing mechanism for the master cam follower 65, reference may be had to the above-mentioned patent.

Rock bar actuating mechanism

The rock bar 49 is normally held in an operative forward position by means of a spring (not shown) so that the master cam opposite the master cam roller 65 is held in engagement with the roller 65 as the master camshaft is rotated so as to cause a rocking of the rock bar 49, causing a corresponding movement of the cam being ground relative to the operative face of the grinding wheel, so that a desired and predetermined contour will be generated on the cam being ground.

It is desirable that a suitable mechanism be provided to rock the bar 49 to an inoperative position, thereby separating the master cams from the follower and the product cams from the grinding wheel before the table traversing movement is started. To accomplish this result, a fluid pressure mechanism may be utilized, such as that shown in the prior Patent No. 1,783,755. This mechanism comprises a cylinder 100 connected by a pipe 101 with a valve 102 which is connected by a rack 103 with a gear train 104 which is rotated by the wheel feeding mechanism. The gear connection between the rack 103 and the feed mechanism is such that when the feed wheel 30 is turned in a clockwise direction to cause a rearward feeding movement of the grinding wheel, this movement serves to shift the valve 102 from the position indicated in Fig. 2 of the drawings and move the valve piston 106 toward the left so as to admit fluid under pressure from pipe 107 through valve 102 and into pipe 101 and cylinder 100, causing a downward movement of the piston (not shown) within the cylinder 100 so as to rock the rock bar 49 to an inoperative position so that the table may be readily traversed to position another cam in operative relation with the grinding wheel. For further details of the rock bar actuating mechanism, reference may be had to the prior patent above referred to.

Taper adjustment—Work support

As illustrated in the drawings, the rock bar 49 is supported in brackets 52 and 53 which are rigidly supported on a swivel table 45, so that the rock bar may be readily adjusted to position the axis of the work parallel to or at an angle with the axis of the grinding wheel spindle. Such a construction permits the angle between the work axis and the wheel axis to be readily varied so that the desired taper may be produced

on the cam being ground. If desired, the machine may be built for a fixed taper, in which case the swivel table 45 may be dispensed with. In this case, the brackets 52 and 53, which support the rock bar 49, are fixedly mounted on the upper surface of table 11 and are positioned so that the axis of the camshaft 57 is positioned at an angle relative to the axis of the wheel spindle 16, so that when the grinding wheel 15 is brought into operative contact with a cam to be ground, the cylindrical operative face of the grinding wheel will grind the cams with a desired and predetermined taper thereon.

Stepped master cams

With the axis of the camshaft set at an angle relative to the axis of the grinding wheel, it will be readily appreciated that if the successive cams on the camshaft 57 are ground from the headstock end toward the footstock, due to the angular positioning of the axis of shaft 57 relative to grinding wheel spindle 16, the rock bar must be rocked through a greater angle when successive cams are ground if it is desired to rely upon the same fixed feed stop abutment to accurately size each of the successive cams as they are ground. To permit the desired additional rocking of the rock bar so as to enable the machine to be operated by a feed mechanism employing a single stop, the master cams 72 are stepped or varied in size from the left-hand end to the right-hand end, as illustrated in Fig. 1. The left-hand master cam is the largest in diameter or size and each successive master cam is smaller in size than the preceding master cam. It will be readily apparent from the illustration in Fig. 1 that when the table 11 is moved toward the left to position cam 110 into operative relation with the grinding wheel 15, the master cam roller 65 will be moved longitudinally toward the right, as viewed in Fig. 1, and into operative relation with master cam 111. The master cam 111 is smaller in diameter than master cam 112 and will allow the rock bar to rock through a greater distance toward the periphery of the grinding wheel so that by utilizing a single adjustment of the stop 33 and stop abutment 32 of the feed mechanism, the cam 110 may be accurately ground to the desired shape and size. The difference in diameter or size of successive master cams is calculated and determined by the amount of taper and spacing of the cams to be ground. It will be readily appreciated from the foregoing disclosure that a plurality of tapered cams may be ground on an integral camshaft by utilizing a true cylindrical grinding wheel without the necessity of providing a complicated multi-stop feed mechanism for controlling the size of the various cams as they are ground.

If desired, the grinding wheel may be readily trued by means of a diamond truing tool 120 which is adjustably positioned on a bracket 121 which is in turn fixed to the swivel table 45 (Fig. 2) or to the longitudinally movable table 11. When it is desired to true the grinding wheel, the operator merely traverses the work table 11 toward the right to bring the diamond into operative contact with the periphery of the grinding wheel so as to true the surface thereof.

The operation of this machine will be readily apparent from the foregoing disclosure. The camshaft to be ground is mounted on centers 58 and 59 and the swivel table is adjusted to the desired angle or the brackets 52 and 53 are rigidly fixed on the table 11 so that the axis of

the shaft 57 bears the proper angular relation with the axis of the wheel spindle 16. The operator then traverses the table 11 by manipulation of the manually operable traverse wheel 80 5 to bring the first cam on the left-hand end of the camshaft 57 into operative relation with the wheel 15. During this positioning movement, the automatic master cam roller indexing mechanism, as shown in Fig. 3, causes the master 10 cam roller 65 to be moved into operative relation with the left-hand master cam 112. The operator then feeds the grinding wheel 15 toward the camshaft 57, by rotating the feed wheel 30, to grind the left-hand end cam to the required 15 diameter. After the first cam has been ground to a predetermined size, the operator rotates the feed wheel 30 in a clockwise direction to move the grinding wheel 15 rearwardly and also to actuate valve 102, admitting fluid under pressure 20 through pipe 101 into cylinder 100 to rock the bar 49 so as to separate the camshaft 57 from the grinding wheel and the master cams 72 from the follower roller 65. The operator then, by manipulation of the traverse wheel 80, traverses the table 11 in a direction toward the left, as viewed in Figs. 1 and 2, to bring the second 25 cam 110 into the position as illustrated in Fig. 1 in operative relation with the grinding wheel 15. This traversing movement of the table 11 automatically indexes the master cam roller 65 30 into operative relation with the master cam 111, and the operator may then by turning the feed wheel 30 in a counterclockwise direction (Fig. 2) cause the grinding wheel to be led into cam 110 35 to grind the same to a predetermined shape and size. The master cam 111 being of smaller diameter than the preceding master cam 112, allows the rock bar to rock to a greater extent so as to compensate for the angular relation of the 40 shaft 57 and permit the grinding wheel to reduce the cam to a required and predetermined size when abutment 32 engages stop arm 33. This sequence of operation is continued until all 45 of the cams on the shaft are ground to the desired extent without the necessity of resetting or adjusting the stop abutment 32 of the wheel feeding mechanism.

While the present invention has been described as applied to a manually operable cam grinding 50 machine, I do not desire to be so limited in interpreting the scope of my invention. My invention is equally applicable to an automatic cam grinding machine of the types shown in the U. S. Patents Nos. 1,840,088 and 1,945,588 and the 55 copending application Serial No. 605,707.

Having thus described my invention, what I claim as new and desire to secure by Letters Patent is:

60 1. A grinding machine comprising a rotatable grinding wheel, means for rotatably supporting a multiple camshaft with its axis at an angle to the wheel axis, and means for moving the wheel and shaft longitudinally relative to each other and parallel with the wheel axis to position successive cams in operative relation with the grinding wheel and means for moving them relatively towards and from each other, so as to grind a predetermined taper on a plurality of cams thereon while in said angular relationship.

70 2. A grinding machine comprising a rotatable grinding wheel, means for rotatably supporting a camshaft with its axis at an angle to the wheel axis, and means for moving the wheel and shaft longitudinally relative to each other and parallel

75 with the wheel axis and means for moving them relatively towards and from each other, so as to grind a plurality of cams thereon while in said angular relationship, said means including a set of master cams of successively variable size and a follower cooperating therewith to move the camshaft and wheel through successively greater distances in grinding the successive cams on the shaft.

3. A grinding machine comprising a rotatable grinding wheel, means for rotatably supporting a multiple camshaft with its axis at an angle to the wheel axis, and means for moving the wheel and shaft longitudinally and transversely relative to each other and parallel with the wheel axis and means for moving them relatively towards and from each other, so as to grind a plurality of cams thereon while in said angular relationship, said means including a set of master cams of successively variable size and a follower 100 cooperating therewith to move the camshaft and wheel through successively greater or successively lesser distances to grind a predetermined tapered surface of a predetermined contour on successive cams on the shaft.

4. A grinding machine comprising a transversely movable slide, a rotatable grinding wheel on said slide, a longitudinally movable work supporting table, means for rotatably supporting a camshaft on said table with its axis arranged at 105 an angle to the wheel axis, and means for moving the wheel and table longitudinally and transversely relative to each other to grind a predetermined tapered surface of a predetermined contour on a plurality of cams thereon while in said angular relationship.

5. A grinding machine comprising a transversely movable slide, a rotatable grinding wheel thereon, a longitudinally movable work supporting table, means for rotatably supporting a camshaft on said table with its axis arranged at an angle relative to the wheel axis, and means for moving the slide and table longitudinally and transversely relative to each other to grind a plurality of cams on said shaft while in said angular 45 relationship, said means including a set of master cams of successively variable size and a follower 50 cooperating therewith to move the camshaft and wheel to successively greater or lesser distances in grinding the successive cams on the shaft.

6. A cam grinding machine comprising a base, a transversely movable slide thereon, a rotatable grinding wheel on said slide, a longitudinally movable table on said base, a rock bar pivotally mounted on said table, a rotatable work support 55 on said bar which is arranged to rotatably support a camshaft thereon, said rock bar and rotatable work support being so positioned and arranged that its axis makes an angle to the path of travel of said table and also with the axis of the grinding wheel, said angle being such as to produce the desired taper on a cam being ground, and means including a master cam roller and a plurality of rotatable stepped master cams arranged to rock said bar and camshaft toward the operative face of the grinding wheel through a greater distance for each successive cam as it is ground.

7. A camshaft grinding machine comprising a base, a transversely movable slide mounted thereon, a rotatable grinding wheel on said slide, a longitudinally movable table on said base, a rock bar pivotally mounted on said table, a rotatable work support on said bar which is arranged to rotatably support a camshaft thereon, said rock 70 75

bar and rotatable work support being so positioned and arranged that their axes of rotation are set at an angle to the path of travel of the table and the axis of the grinding wheel, said angle being such as to produce the desired taper on a cam being ground, a master camshaft on said rock bar arranged in axial alignment with the camshaft being ground, a master cam follower rotatably and slidably mounted on said table, and a plurality of stepped master cams on said shaft, said master cams varying in size so as to allow the rock bar and camshaft to rock a greater distance toward the wheel periphery for each successive cam being ground.

8. A camshaft grinding machine comprising a base, a transversely movable wheel slide mounted thereon, a rotatable grinding wheel on said slide, a longitudinally movable table on said base, a rock bar pivotally mounted on said table, a rotatable work support on said bar which is arranged to support a camshaft thereon, said rock bar and rotatable work support being so positioned and arranged with its axis at an angle to the path of travel of said table and the axis of said grinding wheel, said angle being such as to produce the desired taper on a cam, a master camshaft on said rock bar arranged in axial alignment with the camshaft to be ground, and a plurality of master cams of stepped sizes on said shaft to allow the camshaft to rock to a greater distance toward the wheel periphery while grinding successive cams on the shaft being ground.

9. A camshaft grinding machine comprising a base, a transversely movable slide mounted thereon, a rotatable grinding wheel on said slide, a longitudinally movable table on said base, a rock bar pivotally mounted on said table, a work support on said bar which is arranged to rotatably support a camshaft thereon, said rock bar and rotatable work support being so positioned and arranged that its axis is set at an angle to the path of travel of the table and the axis of the grinding wheel, said angle being such as to produce the desired taper on a cam being ground, a master camshaft on said rock bar arranged in axial alignment with the camshaft being ground, a master cam follower rotatably and slidably supported on said table, and a plurality of stepped master cams on said shaft, said master cams varying in size so as to allow the rock bar and camshaft to rock a greater distance toward the wheel periphery for each successive cam being ground.

10. A camshaft grinding machine comprising a base, a transversely movable slide thereon, a rotatable grinding wheel on said slide, a longitudinally movable table on said base, means to traverse said table longitudinally, a rock bar pivotally mounted on said table, a rotatable camshaft support on said bar, the axes of the rock bar and rotatable support being positioned and arranged at an angle to the path of travel of said

table and also with the axis of the grinding wheel, said angle being such as to produce the desired taper on a cam being ground, and means including a master cam roller and a plurality of rotatable stepped master cams arranged to rock said bar and camshaft toward the operative face of the grinding wheel through a greater distance for each successive cam as it is ground.

11. A camshaft grinding machine comprising a base, a transversely movable slide mounted thereon, a rotatable grinding wheel, a longitudinally movable table on said base, means to cause a relative transverse movement between the wheel and said table, means to cause a longitudinal traversing movement between the wheel and said table, a rock bar pivotally mounted on said table, a rotatable work support on said bar which is arranged to rotatably support a camshaft thereon, said work support being so positioned that its axis makes an angle to the path of travel of the table and the axis of the grinding wheel for producing the desired taper on the cam being ground, a master camshaft on said rock bar having a plurality of stepped master cams thereon, and means to cause a relative indexing movement between said follower and master camshaft as the table is moved longitudinally, said master cams being of successively varying sizes so that in grinding successive cams, the camshaft and rock bar may be rocked through a varying distance and the cam being ground may be accurately sized by utilizing a single stop on the wheel feeding mechanism.

12. A cam grinding machine comprising a base, a transversely movable slide thereon, a rotatable grinding wheel, a longitudinally movable table on said base, a rock bar pivotally mounted on said table, a rotatable work support on said bar which is arranged to rotatably support a camshaft thereon, said rotatable work support being so positioned and arranged that its axis makes an angle to the path of travel of the table and the axis of the grinding wheel for producing the desired taper on the cam being ground, means to traverse said table longitudinally to position successive cams opposite to the grinding wheel, a wheel feeding mechanism arranged to feed the grinding wheel relatively toward and from the work to reduce the cam to a predetermined size, a stop to limit the forward feeding movement of the grinding wheel, and means including a plurality of rotatable stepped master cams and a follower which are arranged to rock said bar and camshaft relatively towards and from the operative face of the grinding wheel, said cams being of successively varying sizes so as to rock the camshaft to a greater or lesser distance in grinding successive cams, whereby each cam may be accurately sized by utilizing a single stop of the wheel feeding mechanism.

CLARENCE J. GREEN.
